UNITED STATES PATENT OFFICE.

JOHN KNIERIEM, OF GLENDALE, NEW YORK, ASSIGNOR TO METROPOLITAN-COLUMBIA MFG. CO., INC., A CORPORATION OF NEW YORK.

DESIGN FOR A LOOP FOR LIGHTING FIXTURES.

Application filed December 9, 1926. Serial No. 19,985. Term of patent 3½ years.

To all whom it may concern:

Be it known that I, JOHN KNIERIEM, a citizen of the United States, and a resident of Glendale, county of Queens, and State of New York, have invented a new, original, and ornamental Design for a Loop for Lighting Fixtures, of which the following is a specification, reference being had to the accompanying drawing, forming a part hereof.

In these drawings:

Figure 1 is an elevational view of the loop for lighting fixtures, the part shown in full line outline being ornamented in the same manner as the part more fully illustrated; and

Figure 2 is a diagrammatic side outline view of the same.

I claim:

The ornamental design for a loop for lighting fixtures substantially as shown.

JOHN KNIERIEM.
